SEWING-MACHINE ATTACHMENT

Herbert H. Russell, New Haven, Conn., assignor
to The Greist Manufacturing Company, New
Haven, Conn., a corporation of Connecticut

Application December 15, 1949, Serial No. 133,059

7 Claims. (Cl. 112—135)

1

This invention relates to a sewing-machine attachment and more particularly to an attachment designed to be attached to the usual household sewing machine in order to make a ruffle or gather in the material fed to the machine.

It is more or less usual in devices of this character to provide a frame adapted to be attached to the presser bar of the sewing machine upon removal of the usual presser foot, and upon this frame is pivoted a pendulum lever connected at its lower end to the reciprocable ruffling blade, the lever in turn being operated by a fork arm pivoted on the frame and having a free end for connection with the needle bar so that the fork arm is actuated upon reciprocation of the needle bar. Also, means are usually provided to vary the spacing apart of the ruffles, that is, to vary the number of sewing-machine stitches between adjacent ruffles, and also to provide an adjustment to make finer or coarser gathers or ruffles.

The present attachment is generally similar to certain prior attachments in the above respects, but differs therefrom in that novel mechanism is provided for adjusting or varying the width of the gathers or ruffles. In the present device the pendulum lever is provided with a shoulder to be engaged by a pawl carried by the fork arm so that the lever is actuated in one direction by the engagement of the pawl with this shoulder. The lever is also actuated by the fork arm in the other direction by the engagement of a lug on the fork arm with a cam-shaped member adjustably mounted on the pendulum lever so that by adjustment of this member the throw of the ruffling blade may be varied.

In the present instance, a toothed member or ratchet is secured to this cam member to rotate therewith and a spring detent or pawl is provided on the pendulum lever to cooperate with the teeth of the ratchet to releasably hold the cam in adjusted positions. Thus, a very fine adjustment may be made so as to adjust the width of the gathers or ruffles to the exact width desired, and also the adjustment can be made easily and conveniently without having to release or tighten any clamping means to secure the cam in a new position.

One object of the present invention is to provide a sewing-machine ruffer of simple and improved construction.

Another object of the invention is to provide a sewing-machine ruffer attachment having new and improved means for adjusting the width of the ruffle or gather.

2

A further object of the invention is to provide a sewing-machine ruffer attachment which is adjustable for various types of work and so constructed that the adjustment may be performed quickly and easily by an untrained operator merely by a rotation of the adjusting button.

To these and other ends the invention consists in the novel features and combinations of parts to be hereinafter described and claimed.

- 10 In the accompanying drawings:
Fig. 1 is a side elevational view of a ruffer attachment embodying my improvements;
Fig. 2 is a similar view taken from the other side of the attachment;
- 15 Fig. 3 is a view similar to Fig. 1 showing the adjusting cam in a different position;
Fig. 4 is a detailed elevational view of the pendulum lever and adjusting cam;
Fig. 5 is an elevational view showing the reverse side of the parts shown in Fig. 4;
20 Fig. 6 is a sectional view on line 6—6 of Fig. 5;
and
Fig. 7 is a top plan view of the adjustable pawl carrier.
- 25 To illustrate a preferred embodiment of my invention, I have shown in the drawings a sewing-machine ruffer attachment comprising a frame 10 having a toe portion 11 to which is secured an adapter 12, by means of which the device may be attached to the presser bar of the sewing machine in the usual manner. Pivoted to the frame at 14 is a pendulum lever 15 which extends downwardly from its pivot point and, at its lower end, is pivoted to a ruffling blade carrier 16.
- 30 Also pivoted to the frame at 14 is the fork arm 18 provided with a forked front end 19 which may be secured to the needle bar so to be oscillated about its pivot point by the reciprocation of the needle bar. At the rear end of the fork arm is an upwardly-projecting finger 20 adapted to be received in one of a plurality of openings 21 provided in a pawl carrier 22 pivoted to the fork arm at 23.
- 35 As is usual the pawl carrier 22 may be swung laterally about the pivot 23 so as to engage the finger 20 in any desired one of the openings 21, and also may be moved vertically about its pivoted end, as it is loosely received upon the pin 23. A spring 24 normally holds the pawl carrier in the position shown in Figs. 1 and 2, but it will be understood that the free end of this member may be raised so as to disengage it from the finger 20.
- 40 45 50 55 Upon the pawl carrier is provided a depending

pawl member 25 adapted to engage a shoulder 26 upon the upper end of the pendulum lever 15 above the pivot 14 so as to actuate this lever and move the ruffling blade forwardly as shown in Figs. 1 and 2 upon an upward stroke of the needle bar. The above construction is more or less usual in devices of this kind and the operation of these parts will be understood without further description.

In order to move the ruffling blade rearwardly after a forward operative movement thereof, the fork arm 18 is provided with a lug or kicker 30 which is adapted to engage a part of the edge of a cam member 31 rotatably or pivotally mounted on the pendulum lever 15 by means of the pivot pin 32. The member 31 is provided with a curved portion 33 eccentric to the pivot 32, and is also provided with a relatively abrupt projection 34 at one end of the eccentric portion 33.

It will be apparent from the drawings that the lug 30 is adapted to engage the parts 33 and 34 of the cam 31 when the fork arm is moved downwardly and thus return the pendulum lever 15, and the ruffling blade attached thereto, to its starting position. The amplitude or length of this return stroke will depend upon the position of the cam member 31. For example, as shown in Fig. 1, the lug 30 is in engagement with the projection 34 and hence will move the ruffling blade rearwardly to the limit of its stroke, thus making a wide ruffle or gather. If, however, the cam member 31 is turned in a counter-clockwise direction, the lug 30 will then attack the edge portion 33 of the cam member 31 and a shorter return stroke of the pendulum lever and ruffling blade will be effected. The radius of the edge portion 33 of the cam member gradually decreases in a direction away from the projection 34 so that the shortest stroke of the lever 15 is effected when the parts are substantially in the position shown in Fig. 3. By a slight additional rotation of the cam member 31 in a counter-clockwise direction, the lug 30 will not contact the edge 33 of the cam member at all during a normal stroke of the needle bar, and, in that position of the parts, plain stitching without ruffling will result.

From the above description it will be apparent that a very fine adjustment of the width of the ruffles may be obtained, provided that the cam member may be set and held in position to cause the lug 30 to attack any desired point on the edge 33 of the cam member 31. For this purpose an adjusting button 36 (Fig. 6) is provided upon the pivot pin 32 of the cam member so that this cam member may be readily rotated by turning the button 36. Also secured to the pivot pin 32 is a segment member or ratchet 37 having upon its edge, as shown in Fig. 5, a plurality of fine teeth 38.

A pawl in the form of a spring member 39 is secured at one end to the pendulum lever 15, as shown at 40, this spring member being curved to generally follow the outline of the edge of the segment member 37 and having a detent 41 at its free end to enter a selected one of the teeth or notches 38. With this construction, it will be apparent that the segment member or ratchet 37 may be easily turned to the desired position by means of the button 36, and that the detent 41 will engage in a selected notch of the toothed portion 38 of the ratchet and releasably hold the cam member 31 in the desired position. It will be understood that the detent

is so formed that the ratchet may be turned in either direction and the detent will be cammed out of the notch in which it is engaged. It will, of course, enter successive notches as the ratchet member is rotated and act as a "click" to inform the user as to the adjustment which is being made.

The pendulum lever 15 is provided with an arcuate slot 42, the radius of which is described about the pivot 32, and the cam member 31 is provided with a pin 43 designed to enter this slot so as to limit the rotational movement of the cam member. As illustrated, the length of this slot is such that the range of movement of the cam member will be substantially that of the arc of the edge of the segment or ratchet member 37, so that the detent 41 will never lie beyond the teeth 38.

It will be obvious that, with this arrangement, very fine adjustments of the cam 33 may be made and when the cam is moved to any desired position, it will be automatically but releasably retained in this position by engagement of the detent 41 with the ratchet teeth 38, and that the loosening and tightening of any screws or clamping members is unnecessary in order to release the cam member for adjustment or to secure it in an adjusted position.

While I have shown and described a preferred embodiment of my invention, it will be understood that it is not to be limited to all of the details shown, but is capable of modification and variation within the spirit of the invention and within the scope of the claims.

What I claim is:

1. A ruffer attachment for sewing machines comprising a frame, a pendulum lever pivoted at its upper end to the frame, a ruffling blade connected to said lever, a fork arm pivoted to the frame having means for connection to the needle bar of the sewing machine and means for actuating said lever, a cam member engaged by said actuating means and having a pivot pin rotatably mounted in said lever, means on the pivot pin by which said cam member may be rotated, and spring detent means for holding said cam member in rotatably adjusted position.

2. A ruffer attachment for sewing machines comprising a frame, a pendulum lever pivoted at its upper end to the frame, a ruffling blade connected to said lever, a fork arm pivoted to the frame having means for connection to the needle bar of the sewing machine and means for actuating said lever, a cam member engaged by said actuating means and having a pivot pin rotatably mounted in said lever, a turnbutton secured to said pivot pin to rotate the same, and spring detent means for holding said cam member in rotatably adjusted position.

3. A ruffer attachment for sewing machines comprising a frame, a pendulum lever pivoted at its upper end to the frame, a ruffling blade connected to said lever, a fork arm pivoted to the frame having means for connection to the needle bar of the sewing machine and means for actuating said lever, a cam member rotatably mounted on said lever, means for rotating said member, a ratchet member secured to the cam member, and a detent carried by the lever and engaging said ratchet member.

4. A ruffer attachment for sewing machines comprising a frame, a pendulum lever pivoted at its upper end to the frame, a ruffling blade connected to said lever, a fork arm pivoted to the frame having means for connection to the

needle bar of the sewing machine and means for actuating said lever, a cam member rotatably mounted on said lever, means for rotating said member, a ratchet member secured to the cam member, and means engaging said ratchet member to hold the cam member in adjusted position.

5. A ruffler attachment for sewing machines comprising a frame, a pendulum lever pivoted at its upper end to the frame, a ruffling blade connected to said lever, a fork arm pivoted to the frame having means for connection to the needle bar of the sewing machine and means for actuating said lever, a cam member rotatably mounted on said lever, means for rotating said member, a ratchet member secured to the cam member and having teeth on an edge portion thereof, and a spring-pressed detent mounted on the lever to engage said teeth and releasably hold said cam member in adjusted position.

6. A ruffler attachment for sewing machines comprising a frame, a pendulum lever pivoted at its upper end to the frame, a ruffling blade connected to said lever, a fork arm pivoted to the frame having means for connection to the needle bar of the sewing machine and means for actuating said lever, a pivot pin rotatably mounted in said lever, a cam member secured to the pivot pin and adapted to be engaged by a part of the fork arm, a member on said pivot

pin having a toothed edge portion, and a spring-pressed detent carried by the lever and engaging the toothed portion of said member to releasably hold the same against rotation.

7. A ruffler attachment for sewing machines comprising a frame, a pendulum lever pivoted at its upper end to the frame, a ruffling blade connected to said lever, a fork arm pivoted to the frame having means for connection to the needle bar of the sewing machine and means for actuating said lever, a pivot pin rotatably mounted in said lever, a cam member secured to the pivot pin and adapted to be engaged by a part of the fork arm, a member on said pivot pin having a toothed edge portion, and a spring member secured at one end to said lever and provided at its other end with a detent engaging the teeth of said member to releasably hold said cam against rotation.
